UNITED STATES PATENT OFFICE.

JAMES C. FRENCH, OF CHICAGO, ILLINOIS, ASSIGNOR, BY MESNE ASSIGNMENTS, TO
F. C. AUSTIN MACHINERY COMPANY, A CORPORATION OF ILLINOIS.

BUCKET CLEANER.

Application filed November 10, 1919. Serial No. 336,942.

To all whom it may concern:

Be it known that I, JAMES C. FRENCH, a citizen of the United States of America, and a resident of Chicago, Illinois, have invented a certain new and useful Improvement in Bucket Cleaners, of which the following is a specification.

This invention relates to excavating apparatus, and more particularly to the means for automatically cleaning out the buckets thereof, such as those on an ordinary trenching machine, so that each bucket will properly discharge its load.

Generally stated, the object of the invention is to provide an improved construction and arrangement whereby each bucket has an individual cleaner by which the load is discharged at the proper time.

It is also an object to provide certain details and features of construction and combinations tending to increase the general efficiency and the desirability of an automatic bucket cleaner of this particular character.

To these and other useful ends the invention consists in matters hereinafter set forth and claimed and shown in the accompanying drawings, in which—

Fig. 1 is a side elevation of the upper portion of an endless series of excavating buckets, such as those employed on an ordinary trenching machine, showing said buckets and other portions of the apparatus in vertical section.

Fig. 2 is a plan of the apparatus shown in Fig. 1.

As thus illustrated, the invention comprises an endless link belt 1, of any suitable character, supported on the rotary member 2 which has a transverse shaft 3, it being obvious that power can be communicated to the endless series of buckets through the medium of this shaft. The member 2 is provided with blades or partitions 4, so that pockets are formed between them to receive the discharge from the buckets 5, on the endless belt. Each bucket, it will be seen, is suitably secured to the pivots 6 and 7 at opposite ends of a single link in the belt, so that each bucket is rigid with one of said links. It will be understood that these buckets are of any suitable width, being wide enough to cut a trench of the desired width, and the outside or front wall 8 of each bucket is curved and formed on the line of a circle struck from the pivot 7 as

an axis. Each bucket has a back wall 9 which serves as the cleaner, and which is supported on the pivot 7, the other edge portion of the cleaner being normally engaged by the stop or shoulder 10 adjacent the pivot 6, so that the load is held in the bucket. The cleaner 9 has a rigid arm 11 which is pivotally connected by a straight link 12 with the crooked link 13, the latter having a curved portion 14 which extends around the pivot 7 when the links are in alinement. However, when the links travel around the member 2, in the manner shown, the relative swinging movement between the two adjacent links to which the crooked link 13 is pivoted at 15 and 16, will cause the cleaner 9 to be swung away from the stop 10 and toward the mouth of the bucket, as shown in Fig. 1, thus scraping the load out of the bucket; and, at about this time the load is thrown into one of the pockets of the rotary member 2, it being borne in mind that the buckets are traveling rapidly and that the discharge of the contents of the buckets occurs while the latter are starting to travel around the supporting member 2, which latter is rotating at the desired speed to operate the endless chain of excavating buckets. As soon as the links straighten out and assume their relative positions in alinement with each other, as shown at the left in Fig. 1, the cleaner 9 of each bucket again assumes its normal position against the stop 10 of its allotted bucket. At such time, as previously explained, the curved portion 14 of the link 13 extends around the pivot 7 and thus holds the cleaner in position to form the back wall of the bucket.

From the foregoing, therefore, it will be seen that each bucket is provided with an individual cleaner by which the contents of the bucket are automatically discharged at the proper time. It will also be seen that the cleaner thus provided for each bucket is automatically controlled by the relative movement of the links, and by the movements which the links have while traveling around the hexagonal or other shaped member 2 which serves as a sort of sprocket to support and operate the endless link belt.

It will be understood, of course, that the materials discharged from the buckets into the pockets of the rotary member 2 are then discharged from the latter onto a suitable conveyer (not shown) or into or onto any-

thing else that may be found suitable for the purpose.

Thus the controlling means for causing the cleaner to eject the load from the bucket 5 are connected to the link belt, so that the latter controls the discharge.

What I claim as my invention is:—

1. In bucket elevators or conveyers, the combination of a link belt, a bucket mounted 10 on said belt, a pivoted cleaner for said bucket, serving as a back wall therefor while the bucket is being filled and while the load is being carried to the desired point of discharge, means to support the link belt, and mechanism controlled by the belt and pivotally connected at spaced points to a plurality 15 of links thereof to operate said cleaner to discharge the load when the desired point of discharge is reached.
2. In bucket elevators or conveyers, the combination of a link belt, a bucket mounted 20 on said belt, a pivoted cleaner for said bucket, serving as a back wall therefor while the bucket is being filled and while the load is being carried to the desired point of discharge, means to support the link belt, and mechanism controlled by the belt to operate 25 said cleaner to discharge the load when the desired point of discharge is reached, said cleaner comprising a plate pivoted at the mouth of the bucket, said mechanism comprising an arm rigid with said cleaner, an element pivoted on the link which carries 30 the bucket and also on the link immediately ahead thereof, and a link connecting said arm with said element.
3. In bucket elevators or conveyers, the combination of a link belt, a bucket mounted 35 on said belt, a pivoted cleaner for said bucket, serving as a back wall therefor while the bucket is being filled and while the load is being carried to the desired point of discharge, means to support the link belt, and mechanism controlled by the belt to operate 40

said cleaner to discharge the load when the 45 desired point of discharge is reached, said cleaner comprising a pivoted plate, said bucket being curved about the axis of the pivot of the plate, and said mechanism comprising links connecting said cleaner with 50 the links of the belt.

4. In bucket elevators or conveyers, the combination of a link belt, a bucket mounted 55 on said belt, a pivoted cleaner for said bucket, serving as a back wall therefor while the bucket is being filled and while the load is being carried to the desired point of discharge, means to support the link belt, and mechanism controlled by the belt to operate 60 said cleaner to discharge the load when the desired point of discharge is reached, said bucket having an open back and a stop shoulder to limit the movement of the cleaner into the bucket, so that the cleaner is held in position to serve as the back wall while 65 the bucket is filling.

5. The improved automatic bucket cleaner, substantially as shown and described, comprising links pivotally connected together and to said cleaner and combined with means 70 connected at medial points on successive links whereby the pivotal action between the links causes the cleaner to eject the load.

6. In a conveyer, the combination of an endless link belt, a bucket on said belt, a 75 cleaner for said bucket, and means pivotally connected to a plurality of links of said belt to operate said cleaner.

7. A structure as specified in claim 6, in combination with rotary member to support 80 said belt and receive the load from the bucket.

8. A structure as specified in claim 6, in combination with a rotary member for supporting and flexing said belt to operate said 85 cleaner.

Signed.

JAMES C. FRENCH.
